UNITED STATES PATENT OFFICE.

RICHARD J. ROSS, OF CHICAGO, ILLINOIS, ASSIGNOR TO GUARANTY IRON & WIRE CO., OF CHICAGO, ILLINOIS, A CORPORATION OF ILLINOIS.

ELEVATOR-DOOR.

1,175,085.

Specification of Letters Patent. Patented Mar. 14, 1916.

Application filed March 23, 1914. Serial No. 826,703.

To all whom it may concern:

Be it known that I, RICHARD J. ROSS, a citizen of the United States of America, and a resident of Chicago, county of Cook, 5 and State of Illinois, have invented certain new and useful Improvements in Elevator-Doors, of which the following is a specification.

This invention relates to fire proof elevator doors of the kind used for freight elevators, in which the closure for each opening is constructed in two parts which are adapted to be shifted in respectively opposite vertical directions when being 10 opened or closed, the two sections being connected together and suitably counterbalanced so as to make their operation easy.

The main objects of this invention are to provide an improved construction of the rib 20 or brace members of the door sections and their connection to the corrugated panels; to provide improved means for retaining the doors against being forced away from the supporting walls transversely to the plane 25 of the door when the doors are in either their opened or closed positions; and to provide improved means adapted to guide the doors in their vertical travel and prevent sidewise shifting, and to yieldingly resist 30 sidewise expansion of the doors so as to prevent buckling or warping when they are subjected to intense heat as in case of fire.

An illustrative embodiment of this invention is shown in the accompanying drawings, in which—

Figure 1 is a view in elevation of an elevator door embodying the foregoing improvements, the view being taken from the inside of the elevator shaft. Fig. 2 is a 40 transverse sectional view of the same. Fig. 3 is a longitudinal sectional view of the same. Fig. 4 is an enlarged sectional detail of a part of the door, the section being taken on the line A—A of Fig. 1. Fig. 5 is an enlarged longitudinal sectional view 45 taken on the line B—B of Fig. 1, the door sections being shown in their closed positions. Fig. 6 is a similar view with the door sections shown in their open positions. Fig. 50 7 is an enlarged fragmentary detail of one corner of one of the door sections showing the arrangement of the spring member which guides the door sections in their normal travel, and which allows for their side- 55 wise expansion when subjected to heat, as in

case of fire. Fig. 8 is a view of the same taken on the line C—C of Fig. 7.

In the construction shown in the drawings, the door sections 1 and 2 are shiftably mounted on suitable guideways secured to 60 the walls or supports 3 bounding the opening or passageway 4, for which they are adapted to form a closure. The door sections are suspended in position by means of cables or chains 5 attached to fittings 6 65 at the lower corners of the upper door section 1 and traveling over pulleys 7 and attached to rods 8 which are connected to fittings 9 secured to the upper corners of the lower door section 2. This suspension 70 of the door sections permits them to be shifted in relatively opposite vertical directions when being moved to their open and closed positions with respect to the opening 75 4, and by reason of the fact that they are connected together their operation is rendered easy.

Each of the door sections comprises a rectangular frame formed of angle bars secured together at their ends and having 80 braces 10 extending across the frames at points between the sides, between which and the sides of the frames the corrugated panels 11 are located. The braces or ribs 10 are herein shown to be formed of sheet 85 metal bent to a V shaped cross section with edge flanges resting on and attached at their ends to the inside of the frame angle bars. The corrugated panels 11 are riveted to the door frames along their edges and 90 are secured to the braces 10 by having their edges bent over as at 12, and interlocked with the bent over portion 13 of the flanges of the braces 10 and secured together by 95 having the bent over parts 12 and 13 firmly forced together, as shown in Fig. 4.

Guideways 14 are formed at opposite sides of the door by means of angle bars 15 and 16 secured together and supported on the wall or supports 3 at the sides of the opening 4, with the flanges 17 of the angle bars 15 spaced away from the wall and extending inwardly toward the door. Angle bars 18 are secured to the sides of the door sections 1 and 2 and have the flanges 19 thereof extending into the guideways 14 (Figs. 7 and 8). The edges of the flanges 17 and 19 overlap a short distance so that their edges are spaced away a considerable distance respectively from the sides of the door sections 110

1 and 2, and the angle bars 16. The overlapping of the flanges 17 and 19 provides a tortuous path for flames to follow in attempting to pass from one side of the door 5 to the other. The space between the flanges and the sides of the door sections and the angle bars 15 is provided so as to allow for a considerable sidewise expansion of the door sections when they are subjected to intense heat, as in the case of fire, and thereby 10 reduce the possibility of buckling or warping as would be the case if no expansion were provided for.

In order to prevent sidewise shifting of 15 the door sections during their normal operation, resilient members 20 are secured to the sides of the door sections and have bowed parts 21 arranged in close proximity to the edges of the flanges 17. These members allow for sufficient play to permit easy operation 20 of the door, and in case of fire will yieldingly resist the sidewise expansion of the door sections up to the point of the bowed parts being flattened out against the 25 sides of the door. Thus when the door becomes cooled and contracts, the member 20 will assume its normal position, and the door will not have been materially injured.

In order to further aid in the preventing 30 of the door sections from becoming forced away from the walls 3, or in case the expansion should exceed that allowed for by the members 20, T-shaped members 22 and 23 are secured to the walls 3 above and below 35 the opening 4 and arranged to have the transverse parts thereof extend into the angle of the brace members 10. The transverse parts of the T-shaped members provide oppositely disposed shoulders 24 and 25 40 which are adapted to engage the flanges of the top and bottom door frame angle bars, when the door sections are in either their open or closed positions. The shoulders 24 on the members 23 also assist in securing the

door section 2 from being forced away from 45 the adjacent wall 3 when the doors are opened and the trucks are being run across the top of the door in passing from the floor to the elevator.

Angle bar members 26 and 27 are secured 50 to the lower side of the upper door section 1 and have their flanges 28 and 29 depending so as to overlap the upper side of the door section 2 when the door sections are in their closed positions. These depending 55 flanges 28 and 29 prevent direct communication from one side of the door sections to the other at the point of their abutting faces, and in case of fire would necessitate the flames following a tortuous path.

Although but one specific embodiment of 60 this invention has been herein shown and described, it will be understood that numerous details of the construction shown may be altered or omitted without departing from 65 the spirit of this invention as defined by the following claim.

I claim:

The combination with suitable upright supports adjacent to an opening, of a door 70 slidably mounted on said supports, said door being shiftable downwardly to its full open position with the top thereof substantially even with and comprising an extension of the floor forming the bottom of said 75 opening, coacting means on said supports and door shaped to enter into interlocking engagement when said door is shifted to said full open position for rigidly supporting the top of said door substantially flush with said 80 floor.

Signed at Chicago this 27th day of Feb., 1914.

RICHARD J. ROSS.
